UNITED STATES PATENT OFFICE.

FORÉE BAIN, OF CHICAGO, ILLINOIS.

DESIGN FOR A FRAME FOR DYNAMO-MACHINES.

SPECIFICATION forming part of Design No. 25,365, dated April 7, 1896.

Application filed December 24, 1894. Serial No. 532,885. Term of patent 7 years.

To all whom it may concern:

Be it known that I, FORÉE BAIN, a citizen of the United States, residing at Chicago, in the county of Cook and State of Illinois, have 5 invented a certain new and useful Design for Frames for Dynamo-Electric Machines, of which the following is a description.

My invention relates to the form or design of frames for dynamo-electric machines such 10 as are used for generating currents or operating as motors, and is illustrated in the accompanying drawings, wherein—

Figure 1 is a side elevation of a frame embodying my design, and Fig. 2 is an end elevation of the same.

Like parts are indicated by the same letter throughout the views.

The main part of the frame is supported on the subbase A, which is substantially rectangular in shape, as shown. Resting upon the subbase A is a cross-shaped or four-armed piece having arms B B carrying the upright supports C C and arms D D, substantially round at the ends, as shown, and gradually increasing in size from the bottom to the top. The substantially cylindrical columns E E are supported upon the arms D D and are of a 20 smaller diameter near the middle than at the ends, the change of diameter being gradual,

as shown. These two columns are connected 30 at the top by the cross-piece F, which is round at the ends to correspond to the shape of the columns E E, and gradually decreases in size from the bottom to the top, as shown.

The essential features of my design, therefore, embrace the substantially rectangular base, the cross-shaped piece thereon having one set of arms that carry the upright supports and another set having round ends and gradually increasing in size from the bottom 40 to the top, two columns substantially cylindrical, except where cut away on one side, supported by said latter arms and having a central portion of smaller diameter than the end portions, the change in diameter being 45 preferably gradual, as shown, said columns being connected at the top by a cross-piece having round ends that conform to the shape of the columns and gradually decreasing in size from bottom to top. 50

I claim—

The design for the frame of a dynamo-electric machine as herein shown and described.

FORÉE BAIN.
